(57) CLAIM

The ornamental design for a transformable carrying case, as shown and described.

DESCRIPTION

FIG. 1 is a perspective view of a transformable carrying case viewed from above;

FIG. 2 is a perspective view of the transformable carrying case of FIG. 1 viewed from below;

FIG. 3 is a top plan view of the transformable carrying case of FIG. 1;

FIG. 4 is a left-side elevation view of the transformable carrying case of FIG. 1;

FIG. 5 is a back elevation view of the transformable carrying case of FIG. 1;

FIG. 6 is a bottom plan view of the transformable carrying case of FIG. 1;

FIG. 7 is a right-side elevation view of the transformable carrying case of FIG. 1; and,

FIG. 8 is a front elevation view of the transformable carrying case of FIG. 1.

The broken lines are directed to unclaimed portions and form no part of the claimed design.
